UNITED STATES PATENT OFFICE.

JOHN E. MAKRENO, OF DETROIT, MICHIGAN.

ARMOR FOR VEHICLES.

1,273,515.

Specification of Letters Patent. Patented July 23, 1918.

Application filed October 24, 1917. Serial No. 198,304.

To all whom it may concern:

Be it known that I, JOHN E. MAKRENO, a subject of the King of Greece, residing at Detroit, in the county of Wayne and State of Michigan, have invented certain new and useful Improvements in Armor for Vehicles, of which the following is a specification, reference being had to the accompanying drawings.

10 This invention relates to armor for vehicles, and has special reference to an armored car or vehicle that may be used for army purposes, for instance, as an ambulance, transport car or fighting unit, although the 15 armor involved in this invention may be used as a shield or protector for other purposes.

My invention aims to provide an armor consisting of a fixed wall and an outer yieldable wall with cushioning members or elements 20 between the walls to support the outer wall relative to the inner wall and at the same time permit of said outer wall yielding when struck with a projectile, to such an extent that the force of the projectile is spent and 25 rebounds by the recoil of the outer wall. Such an armor can be advantageously used as an inclosure for a motor vehicle employed as a fighting unit of an army, the armor having openings for observation purposes 30 and for guns and as the armor must necessarily form the outer part of the car or vehicle, the interior of the car or vehicle may be designed for various purposes.

My invention will be hereinafter specifically described and then claimed, and reference will now be had to the drawing, where- 35 in—

Figure 1 is a side elevation of an armored vehicle, partly broken away and partly in 40 section;

Fig. 2 is a cross sectional view of the same;

Fig. 3 is an enlarged detailed sectional view of the armor.

The armor comprises a fixed wall 1 and 45 connected to said wall are a plurality of bolts or guides 2. Loose on these bolts or guides is an outer yieldable wall 3 having openings 4 for the outer ends of the bolts or guides and the outward movement of said wall is 50 limited by the heads of said bolts or guides.

Interposed between the fixed and movable walls 1 and 3 are a plurality of coiled compression springs 5 and these springs maintain the outer wall 3 normally in engagement 55 with the heads of the bolts or guides 2, but permit of said outer wall yielding or moving

inwardly relatively to the fixed wall 1. The springs 5 are closely assembled and the inner convolutions thereof are fitted over bosses 6 carried by the outer face of the wall 1, while 60 the outer convolutions of said springs receive the shank portions 7 of buffers 8 interposed between the outer ends of the springs and the outer movable wall 3. The buffers 8 are preferably made of rubber and co- 65 operate with the springs 5 in cushioning the outer movable wall 3 relatively to the inner wall 1.

Connecting intermediate convolutions of the springs are rods or springs 9, constituting coupling members, which cause a plurality of springs to coöperate in cushioning an inward movement of the outer movable wall 3 when struck by a projectile or other object. 70

Considering the armor in connection with a vehicle, the armor may be made in sections suitably connected together so as to provide protecting walls or an armor about the chassis of a motor driven vehicle. As 80 such, it has been illustrated in Figs. 1 and 2, wherein the chassis 10 has individual axles 11 for the wheels 12 of the vehicle, said individual axles being provided with springs 13 for supporting U-shaped body frames 14. 85

At the forward end of the chassis 10 is a conventional form of power plant 15, and this power plant includes all those necessary appurtenances, such as a fuel supply system, a cooling system, ignition system, and transmission and steering mechanisms, so the vehicle may be easily operated. The design of the body frames 14 is such as to support side walls, front and rear walls, and a top wall or roof, all of which are made of 95 armor, such as shown in Fig. 3. It is preferable to have a portion of the front wall inclined, as shown in Fig. 1, and provided with observation openings 15^a with the openings of the outer movable wall adapted to be 100 closed by closures 16. The front wall also has air inlet openings for the radiator of the power plant 15, and the rear wall has a suitable door 17 so that soldiers or persons may enter the vehicle. When the vehicle is 105 used as a fighting unit, the armored walls thereof may be provided with openings 18 which will permit of guns within or projecting from the openings being operated by the occupants of the vehicle. 110

It is thought that the utility of my invention, particularly for war purposes, will be

apparent without further description, and while in the drawing there is illustrated a preferred embodiment of my invention, it is to be understood that the structural elements 5 are susceptible to such variations and modifications as fall within the scope of the appended claim.

What I claim is:—

An armor comprising a fixed inner wall, 10 cylindrical bosses carried thereby, an outer movable wall, buffers on the inner face of said wall having shanks in the axes of said cylindrical bosses, coiled compression springs having the inner convolutions 15 rounding said bosses and engaging said inner wall and the outer convolutions bearing

against said buffers and surrounding the shanks thereof, resilient coupling members connecting the intermediate convolutions of said springs and independent of walls, and 20 a plurality of bolts carried by said inner wall and extending through said outer wall with the heads thereof limiting the outward movement of said outer wall relative to said inner wall. 25

In testimony whereof I affix my signature in the presence of two witnesses.

JOHN E. MAKRENOS.
